MANTLES

Harold F. Zimmerman, Louisville, Ky., assignor to the United States of America as represented by the Secretary of the Army

Application December 7, 1951, Serial No. 260,555

5 Claims. (Cl. 67—98)

(Granted under Title 35, U. S. Code (1952), sec. 266)

The invention described herein, if patented, may be manufactured and used by or for the Government for governmental purposes without the payment to me of any royalty thereon.

The present invention relates to mantles for gasoline burning devices, such as lanterns, and more particularly to a mantle incorporating improved means for anchoring the same to a burner tip.

Heretofore, asbestos drawstrings have commonly been provided in the open end or mouth of the mantles used on gasoline burning devices for contracting the mouths of the uncalcined mantles into firm gripping engagement with the burner tips to anchor the same thereto. In order to secure best results with mantles of this type, it was necessary to arrange more or less uniform pleats or tucks in the open mouth of the mantle as the mouth was being contracted by the drawstring. This operation was often awkward to perform because of the relatively inaccessible position in which the burner tips in gasoline lanterns and other gasoline burning devices frequently are located. The mantle of the present invention eliminates these disadvantages of existing mantles by substituting an elastic binding means for the asbestos drawstring heretofore used to anchor mantles to burner tips. Moreover, since the elastic binding means of the present invention disintegrates by the time the mantle has been completely calcined, the mouth of the mantle thereafter is free from external binding forces and the internal strains that might be set up thereby so that the improved mantle has a longer useful life.

Accordingly, an object of the invention is to provide a new and improved mantle for a gasoline burning device, such as a lantern, which mantle is constructed with an elastic open end or mouth for snugly gripping the burner tip upon which it is placed.

Another object of the invention is to provide a new and improved mantle for a gasoline burning device, which mantle has a substantially uniformly pleated or tucked open end or mouth and an elastic loop-shaped binding means in the mouth to maintain the uniformity of the pleats or tucks and to contract the mouth into firm gripping engagement with the burner tip upon which the mantle is placed.

Another object of the invention is to provide a new and improved mantle for a gasoline burning device, which mantle has a substantially uniformly pleated or tucked open end or mouth and an elastic loop-shaped binding means in the mouth to maintain the uniformity of the pleats or tucks and to contract the mouth into firm gripping engagement with the burner tip upon which the mantle is placed.

A further object of the invention is to provide a new and improved mantle for a gasoline burning device, such as a lantern, which mantle is bound to a burner tip by a carbonaceous looped binding means that is elastic at normal temperature and disintegrates at the ambient temperatures prevailing at the burner tip upon completion of the calcining of the mantle and during normal

operation of the burner so that the mantle is free of external binding forces which might be present if the mantle were bound by a non-disintegrable binding member having a different coefficient of expansion than the body of the mantle, such, for example, as an asbestos drawstring.

A still further object of the invention is to provide a new and improved mantle for gasoline lanterns or the like which is inexpensive to construct, more convenient to place in position for use and more durable than conventionally constructed mantles.

These and other objects, advantages and capabilities of the invention will become apparent from the following description and accompanying drawings in which:

Fig. 1 is a side elevational view of the improved mantle of the present invention before the volatile fabrics have been burned out of the same.

Fig. 2 is a vertical cross sectional view of the improved uncalcined mantle of the present invention mounted on a burner tip.

Fig. 3 is a diametrical sectional view on the line 3—3 of Fig. 2.

Fig. 4 is a diametrical sectional view similar to Fig. 3 but showing the mantle after it has been calcined and;

Fig. 5 is a side elevational view of the improved mantle of the present invention after it has been calcined.

The mantle indicated in its entirety by the number 10 has a body 12 of woven or knitted fabric which may be generally similar to the body of a conventional inverted mantle and may be manufactured in much the same manner from material of the same type. In other words, the body of the mantle is of generally slightly elongated globular shape, and it has an open end or mouth 14 along which the body fabric is turned inwardly to form a hem 16 (Fig. 1). Since considerable shrinkage occurs in the body of a mantle during the preliminary process of burning out the volatile portion of its fabric, the body 12 and mouth 14 are generally made at least double the size which it is desired that they ultimately assume.

An asbestos drawstring laced through the mouth of the mantle has heretofore been used to contract the mouth into firm gripping engagement with a burner tip for holding the uncalcined mantle on the burner tip. In place of this drawstring, the improved mantle of the present invention has a looped elastic binding means 18 somewhat smaller in size when relaxed than the outside of the burner tip which is indicated at 20 in Fig. 2. This binding means may comprise one or more loops of elastic thread interlaced, threaded or otherwise intertwined in the hem 16 (Fig. 1), for example, in much the same manner as asbestos cords have heretofore been interlaced in the mouths of mantles, or it may be inclosed within the hem or fixed to the mouth of the mantle in any other manner found convenient. Inasmuch as the binding means 18 has a relaxed size less than the perimeter of the uncalcined mantle 10, the mouth 14 of the mantle will be contracted when the looped binding means 18 is threaded through or otherwise secured therein. In order to take up or accommodate for this contraction, the woven material at the mouth 14 preferably is arranged in substantially uniform pleats or tucks which allow the mouth to expand when the mantle is to be placed over the burner tip 20. These tucks or pleats are shown in a somewhat exaggerated manner at 22 on the drawing.

It will be apparent, therefore, that the improved mantle of the present invention is much more readily placed on a burner tip than a conventional mantle particularly when the tip is in a relatively inaccessible location because the need for attempting uniformly to arrange tucks in the mouth of the mantle while a drawstring is being tightened and the need for tying a knot in the tightened drawstring

is eliminated. The mouth of the mantle of the present invention is merely stretched and slipped over the burner tip 20. Uniformity in the arrangement of the tucks or pleats 22 is maintained when the mouth of the mantle is stretched due to the fact that the elastic loop 18 is threaded through these tucks.

In addition to the ease of placement which results from the substitution of elastic binding means 18 for a conventional asbestos drawstring, the improved mantle of the present invention is also superior to conventional mantles because this elastic binding means permits a more uniform shrinkage of the mouth around the burner tip than is possible when a mantle is anchored by means of a drawstring. As a result, internal stresses in the calcined mantle are greatly reduced or are entirely absent.

In order to obtain this advantage, the elastic binding means 18 preferably comprises a loop of elastic thread made from synthetic rubber-like material which melts and forms a mild adhesive of sufficient strength to hold the mantle 10 on the burner tip 20 during initial burning out of the mantle and which disintegrates in the presence of the temperature prevailing at the burner tip upon completion of burning out of the mantle or during initial burning of gasoline vapor in the mantle. The mantle 10, like conventional mantles, shrinks considerably during this initial burning out process, and its mouth 14 tends to conform to the shape of the burner tip 20, which is provided with an outwardly rounded or flaring periphery forming a retaining ledge or ridge 24 which prevents the mouth of the calcined shrunken mantle from slipping off the burner tip 20 after the binding loop 18 disintegrates. Such disintegration ordinarily occurs by the time heating of the mantle has been continued long enough completely to burn out the volatile materials therein, but, if it has not occurred by then, it will occur almost immediately after the gasoline burner is turned on to burn gasoline vapor in the mantle. The tucked or pleated mouth 14 is then completely free of external restraint such as that afforded by the asbestos drawstrings now used to anchor conventional unburned mantles to burner tips. Since there are no external restraints on the mouth 14 of the mantle 10, it will shrink more uniformly around the burner tip 20 and with less likelihood of internal strains being set up in the mantle. In addition, more even combustion occurs at the mantle and it has for this reason among others a longer useful life.

Another reason for its longer, useful life results from the fact that the tucks or pleats 22 are free to open up, if necessary, to provide for contraction of the mouth 14 whereas this is not true when the mouth of a mantle is bound by a non-disintegrable means, such as an asbestos drawstring of the type heretofore commonly used, even though this cord may expand somewhat. Such a drawstring, nevertheless, continues to have a binding effect on the tucks or pleats in the mouth of the mantle and, furthermore, the rate of expansion of asbestos cord is less than the rate of expansion of the mouth of the mantle so that an additional binding force is set up in the mouth of a mantle by the asbestos drawstrings heretofore used. This is entirely absent from the improved mantle of the present invention.

While a preferred embodiment of the invention has been shown and described, it will be apparent that numerous variations and modifications thereof may be made without departing from the underlying principles of the

invention. It is desired, therefore, by the following claims, to include within the scope of the invention, all such variations and modifications by which substantially the results of the invention may be obtained through the use of substantially the same or equivalent means.

What I claim is:

1. A mantle for a gasoline burner comprising a woven sack-shaped body having a mouth adapted loosely to fit over the tip of said burner, and a loop of elastic carbonaceous material fixed in the mouth of said mantle to contract the said mouth into firm gripping engagement with a burner tip when it is placed on the latter.

15 2. A mantle for a gasoline burner comprising a woven sack-shaped body having a hemmed mouth adapted loosely fit over the tip of said burner, and one or more looped elastic carbonaceous strands intertwined in the hemmed mouth of said mantle to contract the said mouth into firm gripping engagement with a burner tip when it is placed on the latter.

15 3. A mantle for a gasoline burner comprising a sack-shaped body of woven uncalcined material having an open end adapted loosely to fit over the tip of said burner and to shrink sufficiently when calcined to bring said open end into firm encompassing engagement with said tip, and a loop interlaced in the open end of said mantle of material elastic at normal temperatures, sticky and viscous in the temperature range to which it is raised when calcining of the mantle is initiated and distintegrable at the temperature to which it is raised before completion of calcining of the mantle, said loop contracting the said open end into firm gripping engagement with the burner tip upon which the uncalcined mantle is placed.

20 4. A mantle for a gasoline burner comprising a sack-shaped body of woven uncalcined material having an open end adapted loosely to fit over the tip of said burner and to shrink sufficiently when calcined to bring said open end into firm encompassing engagement with said tip, and a loop of synthetic rubber-like material secured in the open end of said mantle of a relaxed size less than the size of the burner tip upon which the mantle is to be used to contract the open end of the uncalcined mantle into firm engagement with a burner tip when it is placed on the latter.

25 5. A mantle for a gasoline burner comprising a sack-shaped body of woven uncalcined material having an open end adapted loosely to fit over the tip of said burner, said uncalcined mantle being adapted to shrink sufficiently when calcined to bring said open end into firm encompassing engagement with said tip, a plurality of substantially uniformly arranged pleats in the open end of the said uncalcined mantle to contract the size of the said end, and a loop of elastic carbonaceous material threaded through said pleated end to maintain the uniformity of said pleats and to contract the said open end of the uncalcined mantle into firm gripping engagement with the burner tip upon which the mantle is placed.
